LESLIE FAWCETT LAMPLOUGH, OF CHICAGO, ILLINOIS, ASSIGNOR TO WESTERN ELECTRIC COMPANY, INCORPORATED, OF NEW YORK, N. Y., A CORPORATION OF NEW YORK.

BRAIDING-MACHINE.

1,295,178.

Specification of Letters Patent. Patented Feb. 25, 1919.

Application filed June 24, 1916. Serial No. 105,581.

To all whom it may concern:

Be it known that I, LESLIE FAWCETT LAMPLOUGH, a subject of the King of Great Britain, residing at 4440 Sunnyside avenue, 5 Chicago, in the county of Cook and State of Illinois, have invented certain new and useful Improvements in Braiding-Machines, of which the following is a full, clear, concise, and exact description.

10 This invention relates to braiding machines, and is particularly useful in connection with braiding machines used for applying the braided covering to telephone switchboard cords.

15 The general object of the invention is to provide new and improved means for drawing the braided cord through the machine and for delivering it at a convenient point. The invention not only increases the efficiency of the machine by reducing the amount of attention which an operator is required to give it, but also improves the quality of the product.

It is well known by those skilled in the 25 art that with the same materials the life of a cord is dependent more or less upon the characteristics of the braided covering, and that the life of a cord is considerably lengthened by an even, uniformly applied braided 30 covering. Further, it is a well-known practice to reinforce the outside covering of a braided cord for that portion of its length which is to receive exceedingly hard usage, thereby giving the cord as a whole an approximately uniform life. This practice is 35 exceedingly advantageous and materially increases the life of cords which are used, together with connecting plugs attached thereto, for making switchboard connections.

40 Cords used for this purpose receive exceedingly hard usage for that portion of the cord immediately adjacent to the connecting plugs, and a reinforced braided covering for this portion of the cord serves to extend its 45 life, by virtue of which the braided cord covering for the entire length of the cord will have a substantially uniform life.

This invention can be used with any of the standard types of braiding machines. In 50 the preferred embodiment of the invention

herein described and illustrated a sinuous or circuitous braider of the New England Butt Braider type is used. To start a braider of this type the operator gathers the ends of the threads which are to be used in forming the desired braid and starts the machine, which is allowed to run until a short length of hollow tube braiding is formed. The machine is then stopped, and the cord which is to receive a braided covering is thrust into the converging threads of the braiding machine, then the machine is again started and the braid is formed about the body of the cord. In braiding cords in this manner, it has been customary in the past, for the operator to start the braid about the body of the cord and feed the cord through the braiding machine manually until a sufficient length of cord had been braided, which would serve as a suitable end to be attached to some standard type of take-up means. Consequently, whenever cords were equipped with a reinforced braided covering, in which case two coverings were applied to a short length at one end of the cord, it was necessary to feed the cord manually for substantially the entire length of the cord to which the reinforcement was being applied. Due to the personal element in the manual feeding of the cord, the rate at which the cord was fed through the braiding machine was not uniform. This naturally resulted in an uneven and nonuniform braided covering, which is very detrimental to the life of the cord.

In the improved apparatus herein described, the manual feed is displaced by an automatic feed, which materially increases the efficiency of the braiding operation and which results in an even and uniform braided covering, thereby producing cords of greater strength and durability and which consequently have a much longer life. In the preferred form of the invention as herein described and illustrated, it is applied to the braiding of telephone switchboard conducting cords of a length varying from about 4 to 8 feet, in which connecting plugs for making temporary connections are attached to the conducting strands at one end of the

100

cords, which ends are, therefore, subjected to extremely hard usage and are consequently served with a reinforced braided covering. The conducting strands at the 5 other end of the cord are withdrawn from the braided covering so that they can be attached to suitable connecting terminals, and the braided covering is continued for a short length as a hollow tube which serves as a 10 stay cord to be attached to a suitable fastener to take the strain off the conducting strands.

In the drawings, which show a preferred embodiment of the invention,

15 Figure 1 is a view in front elevation of the complete machine;

Fig. 2 shows a horizontal section on the line 2—2 of Fig. 1, looking in the direction of the arrows and showing the automatic 20 cord feeding mechanism and the means for transmitting the power to said mechanism;

Fig. 3 is an enlarged front elevation of the cord feeding means and the cord receiving means;

25 Fig. 4 is a side elevation of the cord feeding and receiving means;

Fig. 5 is a horizontal section of the cord guiding means on the line 5—5; and

30 Fig. 6 is a sectional view of a cord which has been served with a reinforced braided covering.

The braiding machine illustrated in Fig. 1 is of the standard New England Butt Braider type. These braiders consist of a 35 circular plate 8, near the outer edge of which are mounted a plurality of spools, the number of which depends upon the number of threads desired in the braid to be formed. These spools are wound with the thread 40 which is to be used in forming the braid, and are mounted in two sinuous tracks, the paths of which cross each other. The spools are given a rotary motion, half of the spools moving in a clockwise and the other half 45 moving in a counter clockwise direction, the spools alternating in the direction of their movement. Because of the design of the sinuous paths in which these spools move and the direction of the movement of the individual spools, each one of the spools moving in one direction crosses the path of one of the spools moving in the other direction immediately after the spools pass each other, and this action of the spools forms the 50 desired interwoven braided covering.

As these braiders are well known in the art, a further description of their operation is considered unnecessary.

The braider is operated by applying any 60 suitable means of power to the shaft 9. The power applied to this shaft is transmitted to the braiding spool apparatus and likewise to the gearing mechanism contained under the gear shield 10. Attached to the upper end 65 of the shaft 9 is a handle 11 provided for

70 manual manipulation of the machine. Adjustably mounted on the shaft 9 is a worm gear 12 which operates a worm wheel 14 which in turn is adjustably mounted on a shaft 15, on the other end of which is adjustably mounted a change gear 16. This change gear 16 meshes with another change gear 17 which in turn, through the beveled gears 18 and 19, as shown in Fig. 2, controls the movement of a shaft 22, to the end of 75 which is attached a roller 20. On the rear end of the shaft 22 is mounted a spur gear 23 which meshes with a second spur gear 24 mounted on a shaft 25, at the other end of which is mounted a second roller 26. The forward end of the shaft 25 terminates in a suitable handle 28. The shaft 22 is rigidly mounted to the cross bars of the braider by means of the plates 29 and 30 which carry suitable bearings in which the shaft 22 rotates. The shaft 25 is pivotally mounted by means of the screw 31 to the rear cross bar of the braider, as shown in Fig. 2. Due to this pivotal mounting this shaft may be swung to the left, thereby materially increasing the 80 distance between the two rollers 20 and 26. Attached to the bearing 26 is a spring 27 which returns the shaft 25 to its normal position as soon as the displacing power applied to the handle 28 is removed. The spur gears 85 23 and 24 on the rear ends of the shafts 22 and 25, respectively, are loosely mounted to allow for this movement of the shaft 25. As shown in Fig. 2, the two rollers 20 and 26 are corrugated, so that they will maintain a good 90 grip on the belts 34 and 35.

95 Mounted on a suitable cross bar 36 is a bracket 37 which carries two pairs of downwardly extending arms 38 and 39, between each pair of which are mounted respectively 100 the rollers 40 and 41. The rollers 40 and 41 are mounted directly above the rollers 20 and 26, respectively, so that the axes of the rollers 20 and 40 are in substantially the same plane, and the rollers 26 and 41 are likewise 105 in substantially the same plane. Interconnecting the rollers 20 and 40 is an endless belt 34 and a similar belt 35 interconnects the rollers 26 and 41. Each of these belts contains in its outer surface a semi-elliptical 110 depression or groove, as clearly shown in Fig. 5. By virtue of the spring 27 the roller 26 yielding holds the outer surface of the belt 35 against the outer surface of the belt 34, and when these belts are thus brought together, the semi-elliptical depression in their outer surfaces forms an elliptical cavity or groove which serves to hold the cord which is being braided and guide it by means of the power driven rollers 20 and 26 to the tubular 115 member 46. The tubular member 46 acts as a receiving or delivery means for the braided cord into which the cord is discharged after it leaves the belts at their point of contact between the rollers 40 and 41, and which de- 120 125 130

livers or directs the cord to a position convenient for removal by the operator. The receiving tube 46 is curved around the side of the machine, as shown in Figs. 3 and 4, by virtue of which the cord which is being braided is automatically delivered to the front part of the machine where it is readily accessible to the operator. When short cords are being braided the end of the braided cord 10 will project from the end of the receiving tube 46, from which the operator will remove it for mounting on a suitable hanger; but if cords of exceedingly long length are being braided, a suitable take-up means can 15 be readily mounted at the end of the receiving tube 46.

The method of braiding cords in connection with the improved automatic feeding device is as follows:

20 Before starting the machine the operator gathers and holds together the loose ends of the threads which are to constitute the braid. The machine is then started and a short end of loose hollow braiding is formed, after 25 which the machine is stopped. The body of a cord is then thrust into the converging threads of the braid, and the braider is again started. As soon as a short length of braid has been attached to the body of the cord, 30 the length of which is determined by the distance between the rollers 20 and 26 and the converging point of the threads 48, as shown in Fig. 1, the operator will swing the roller 26 to the left and place the cord in 35 the elliptical groove formed by the belts 34 and 35. The cord will then be automatically raised due to the gripping effect exerted by the rollers 20 and 26, through the medium of the belts 34 and 35, and be fed 40 through the braider at an even, predetermined rate.

As the braided cord is raised by the rollers 20 and 26, it is guided by means of the elliptical groove in the belts 34 and 35 to the receiving tube 46, from where the tube guides the braided cord to any suitable form of take-up means, in the case of long cords, or from which the cord is removed by the operator when short cords are being braided. 45 In the operation of elevating the cords, it is necessary that the belts 34 and 35 should be held in suitable tension, and for this purpose the downwardly extending arms 38 and 39 may be raised and lowered by means of 50 the adjustment screw 49. The speed of travel of the belt can be readily adjusted by using different combinations of the change gears 17 and 16. To offset changes of dimension in these gears, the worm gear 12 and the change gear 16 are slightly adjustable on the shafts 9 and 50, respectively. The speed of travel of the belts necessarily determines and is directly proportional to 55 the number of turns per foot and the closeness of the braided covering which is ap-

plied to the cord, and consequently the cord feeding device is equipped with this adjustable gear mechanism, so that the number of turns per foot in the braid can be readily changed as desired. When the number of 70 turns per foot has been determined upon and the machine adjusted for that type of braid, the automatic feeding mechanism will apply a braided covering with a uniform number of turns per foot, which it is impossible to 75 obtain when the cord is manually pulled or fed through the braider by the operator.

The method of applying a reinforced braided covering to cords, such as shown in Fig. 6, will now be described:

80 These cords are of comparatively short length and are fed through the braider and the feeding or elevating device one after another, the cords which have been served with braiding being delivered to the operator through the receiving tube 46. In applying the reinforced braided covering to cords of this type, the braider is started and a short end of loose braided sleeving is 85 formed. The body of the cord 47 is then pulled through the converging threads of the braider for a distance equal to the length which it is desired to reinforce. The roller 26 is then displaced to the left and the body of the cord remaining above the braid is 90 placed between the belts 34 and 35. The roller 26 is then allowed to return to its normal position, and the cord is firmly gripped in the elliptical groove 54 in the middle of the belt, due to the tension exerted by the spring 27 which holds the shaft, on which the roller 26 is mounted, to the right, bringing the two surfaces of the belt 95 34 and 35 in close contact.

The machine is then started and the cord is drawn upward through the braid by the action of the rollers 20 and 26, which automatically feeds the cord through the braider at a desired, predetermined rate, depending upon the type of braid desired. When the reinforced braid 100 55 has been applied to the body of the cord, the machine is stopped and the roller 26 moved to the left and the cord removed from the belts. The ends of the cord are now reversed in position, that is, the cord is rotated through an arc of 180 degrees. In this position the entire length of the cord extends downwardly from the point 48 at 105 which the braiding threads converge. The operator now arranges the threads at the turn 56 in the braid, when the braiding machine is again started. The cord is then fed 110 through the braider manually for a very short distance, sufficient to allow the rollers 20 and 26 to firmly grasp the cord, after which the cord is automatically drawn through the braid by the action of the rollers, and requires no further attention until 115 the complete body of the cord has been served, with a braided covering. When the 120

cord has been completely covered with the braided covering, the conducting strands of the cord 57 are pulled through the threads of the braider, and a loose end of braiding 58 is formed and the braider stopped. This end 58 serves as a stay cord which is used to take the tension off the conducting strands 57, and in the operation of braiding likewise serves to hold the braiding threads in proper relation at their converging point 48, so that the next cord to be braided can be thrust through the converging threads of the braider for the application of the reinforced braided covering 55. When this second cord is thus thrust through the braiding threads, the roller 26 is again moved to the right and the second cord to be braided is placed between the belts 34 and 35 together with the cord just preceding which has been served with a complete covering. The machine is then started and the reinforced braided covering 55 is applied to the second cord, both cords being automatically fed through the braider by the action of the rollers 20 and 26. As soon as a portion of the reinforced braiding 55 is applied to the second cord coming through the braider, the stay cord 58 of the first cord is severed, thus disconnecting the first cord from the second cord. The first cord after leaving the upper rollers 41 and 40 is fed into the receiving tube 46 which carries the reinforced end of the cord through the tube to a position where it can readily be reached by the operator, and when the cords are disconnected the operator removes the finished cord from the receiving tube.

The above operation just described is repeated for each cord which is inserted in the braiding machine to receive a reinforced braided covering.

It will be obvious from the above description that the feeding of the cord through the braider is automatically accomplished, except for the very short distance required to start the braid on the body of the cord, which is manually performed by the operator. This short length of braid on the end of the cord is required so that the feed rollers 20 and 26 can properly grip the cord. Thus the feeding operation is substantially automatic and the braided covering which is applied is uniform and even and consequently possesses greater strength and durability. Likewise it will be apparent as a result of this automatic feed that an operator will be able to supervise a greater number of machines, because her attention is only required at the machine for the very short period during which the braided covering is started and when the braided covering has been completely applied. For this reason the efficiency of machines for braiding cords is greatly enhanced by the improvements hereinbefore described.

While the preferred form of apparatus as herein disclosed and illustrated is applied to the braiding of cords of the telephone switchboard type, this invention is not limited to this specific use, but is useful in braiding machines in general.

What is claimed is:

1. In a device of the character described, the combination with a cord braiding machine, of two sets of longitudinally separated guide rollers for receiving and drawing the cord through the braiding machine, and endless grooved belts traveling over said sets of rollers for guiding said cord from one set of rollers to the other. 75

2. In a device of the character described, the combination with a cord braiding machine, of a pair of parallel rollers for gripping and feeding the cord, of a second pair of parallel rollers placed above the first 85 pair, of flexible members interconnecting the lower and upper pairs of rollers, said flexible members having a groove in the outer surface of each of said members which serves to guide said cord. 90

3. In a device of the character described, the combination with a cord braiding machine, of a pair of parallel rollers for gripping and feeding the cord, a second pair of parallel rollers placed above the first 95 pair, a pair of flexible members interconnecting the upper and lower pairs of rollers, said members having a suitable groove in their outer surfaces which serves as a guiding means for said cord, and a receiving 100 means to automatically receive said cord when it leaves said flexible members.

4. In a device of the character described, the combination with a cord braiding machine, of means for gripping the cord immediately after it leaves the braider, means to rotate said gripping means at a uniform speed whereby the cord is automatically fed at a uniform rate through the braider, of a pair of flexible belts which serve to guide the cord after it leaves said gripping means, and a tubular member for receiving said cord after it leaves said guiding means. 110

5. In a machine for braiding short length flexible conducting cords, cord braiding mechanism, means for delivering the braided cord to a predetermined position, and means for directing the braided cord to said delivery means. 115

6. In a machine for covering short length flexible conducting cords, braiding mechanism, and means for delivering the braided cord to a predetermined position. 120

7. In a device of the character described, the combination with a cord braiding machine, of a combined drawing and delivery means for delivering a braided cord to a predetermined position. 125

8. In a device of the character described, the combination with a cord braiding ma- 130

chine, of a guide means for guiding a braided cord to a receiver at a predetermined position.

9. In a device for braiding flexible conducting cords, cord braiding mechanism, and a guide means for guiding the braided cord to a receiver at a predetermined position.

tion, part of said guide means being power driven.

In witness whereof I hereunto subscribe my name this seventeenth day of June, A. D. 1916.

LESLIE FAWCETT LAMPLOUGH.
